UNITED STATES PATENT OFFICE.

SAMUEL BARKER, OF PROVIDENCE, RHODE ISLAND.

DYEING-MACHINE.

1,141,301.

Specification of Letters Patent. Patented June 1, 1915.

Application filed November 10, 1914. Serial No. 871,382.

To all whom it may concern:

Be it known that I, SAMUEL BARKER, a subject of Great Britain, residing at Providence, in the county of Providence and State 5 of Rhode Island, have invented a new and useful Improvement in Dyeing-Machines, of which the following is a specification.

My invention has reference to an improvement in dyeing machines and more particularly to an improvement in that form of dyeing machine in which the yarn is dyed on the beam or in the form of cops, cheeses, crosswound bobbins, etc., and in which the dyeing liquor has a forward and a reverse 10 flow through the beam, cops, cheeses, etc. In the usual construction of such dyeing machines, as heretofore constructed, the beam, cops, cheeses, etc., are held in a vertical position and in an entirely inclosed 15 vat or keir, also a centrifugal pump and a plurality of valves are usually used to control the forward and reverse flow of the dyeing liquor. In these closed machines the 20 yarn after being dyed on the beam is removed from the dyeing machine, the surplus dyeing liquor extracted and the yarn dried separately from the dyeing machine, whereby a material amount of surplus dyeing 25 liquor is lost.

The object of my invention is to improve the construction of a dyeing machine whereby 30 yarn may be dyed on the beam, the surplus dyeing liquor extracted from the yarn and the yarn dried all without removing the 35 yarn from the dyeing machine.

A further object of my invention is to construct a dyeing machine so that the surplus dyeing liquor extracted from the yarn and heretofore lost, is now extracted in the 40 dyeing machine, saved and again used for dyeing.

Another object of my invention is to provide a twin open top tank dyeing machine for sample dyeing or for dyeing a comparatively 45 small amount of stock, whereby one or both tanks may be used for dyeing, extracting and drying the yarn.

Further objects of my invention are to simplify the construction and operation of 50 a twin open top dyeing machine, whereby yarn may be dyed on the beam, the surplus liquor extracted and saved in the machine, all valves eliminated, the dyeing greatly improved and the amount of dyeing liquor

and time heretofore required materially reduced.

My invention consists in the peculiar and novel construction of a valveless open top twin dyeing machine, in which the yarn is dyed on the beam, the surplus dyeing liquor 60 extracted from the dyed yarn in the machine and the yarn on the beam dried in the machine, said dyeing machine having details of construction as will be more fully set forth hereinafter and claimed. 65

Figure 1, is a top plan view of my improved dyeing machine. Fig. 2, is a side view of the dyeing machine showing a beam in the extracting and drying position in dotted lines. Fig. 3, is a vertical transverse 70 sectional view through the dyeing machine taken on line 3. 3. of Fig. 1, and Fig. 4, is a vertical longitudinal sectional view through the machine taken on line 4. 4. of Fig. 1, showing a beam in the lower dyeing position 75 in full lines and in the upper extracting and drying position in dotted lines.

In the drawings, 5, 5, indicates two open top twin tanks, each tank 5 having a dyeing chamber 6, closed at the bottom sides and 80 ends and open at the top. This dyeing chamber is slightly longer and wider than the usual beam used for dyeing yarn and is preferably rounded at the bottom as shown in Fig. 3. Each tank 5 is supported on a 85 base 7 having the legs 8, 8. A central raised portion 9 of each end of the tank is carried above the open top of the tank for the purpose as will be hereinafter described. One end of each tank supports a lower and an 90 upper screw-clamp 10, 10, each of which are in screw-threaded engagement with a nut member 11 secured to the end of the tank. The lower nut member 11 is secured in a central position at the bottom of the tank 95 and the upper nut member 11 is secured in a central position parallel with and directly above the lower nut member 11 to the upper end portion 9 of the tank. Each screw-clamp 10 has a hand wheel 12 on its outer end and a clamping head 13 on its inner end provided with a packing ring in its face. A rotary pump 14 of any usual construction is placed at the opposite end of the tanks 5, 5. A branched pipe fitting 15 100 operatively connects the pump 14 with a pipe connection 16 at the end of each dyeing chamber 6, adjacent the bottom. A lower

- head 17 having a packing ring in its face is connected by a pipe end 18 to each pipe connection 16 at the end of the tank and on a straight axial line with its corresponding head 13 on a clamp-screw 10 at the bottom of the tank. A pipe 19 operatively connects the pump 14 with a branched pipe fitting 20 which in turn is connected by pipes 21, 21 to the bottom of each of the dyeing chambers 6, 6. On the raised central portion 9 of each tank is formed a pipe connection 16 to which a pipe 22 is connected. An upper head 17 having a packing ring in its face is connected by a pipe end 18 to the pipe connection 16 on a straight axial line with its corresponding head 13 on a clamp-screw 10 at the top of the tank, as shown in Fig. 4. The pipe 22 leads to a source of dry air supply, not shown.
- 20 For dyeing yarn in the beam the usual beam 23 having a hollow perforated center is used, as shown in Fig. 4. For dyeing yarn in the form of cheeses, cops, cones or crosswound bobbins, a device suitable for 25 this purpose but not shown or claimed, may be used. When only one dyeing chamber is required for use the pipe openings into the chamber are closed in any suitable manner. Either one or both dyeing chambers 30 may be used at any one time, and where only one of the dyeing chambers is used only one-half of the quantity of dyeing liquor is required.
- In the operation of my improved dyeing 35 machine a beam 22 may be secured in each chamber 6, 6 at the bottom with one open end of the beam on the face of the lower head 17, over the opening in the pipe end 18 and the other end of the beam against the 40 face of the lower clamping head 13. The beam is now firmly clamped in place against the head 17 by turning up the lower clamp-screw 10. A comparatively small amount of dyeing liquor is placed in each dyeing 45 chamber 6, 6, and the rotary pump 14 operated to draw the dyeing liquor from the bottom of each chamber through the pipes 21, 20, 19 and pump 14 and force the liquor through the pipes 15, 16 and 18 and through 50 the beams 23, 23, back into the chambers. This circulation of the dyeing liquor as indicated in full lines in Fig. 2 is kept up for a predetermined length of time, the pump then reversed and the dyeing liquor forced 55 to flow in the reverse direction, from the beams back into the dyeing chambers. This forward and reverse flow of the dyeing liquor is continued until the dyeing process is completed in a comparatively short period. 60 of time and without the use of valves. After dyeing, the beam is raised to the upper or extracting position, and clamped in place by the upper screw-clamp 10, as indicated by dotted lines in Fig. 4, with the 65 open end of the beam against the face of the upper head 17. Dry air, from a source of air supply not shown, is now forced through the pipes 22, 16, 18 and through the beam 23 thereby extracting the surplus dyeing liquor from the yarn which dyeing 70 liquor falls by gravity back into the chamber 6 and is saved. The flow of dry air is continued until the yarn is sufficiently dried for removal from the machine. Also simultaneously with the extracting and drying 75 of the yarn in the upper position a beam could be dyed in the lower position, thereby materially saving in time and practically doubling the capacity of the machine.
- Having thus described my invention, I claim as new:
1. In a dyeing machine, an open top tank, means for operatively supporting a beam in the tank adjacent the bottom, means for operatively supporting a beam over the tank, means for forcing dyeing liquor through the yarn on the beam in the lower position and means for connecting the beam in the upper position to a source of dry air supply. 90
2. In a dyeing machine, an open top tank, means for clamping a beam in the tank in a lower position, means for clamping a beam above the tank, means for forcing dyeing liquor through the yarn on the beam in the lower position and means for connecting the beam in the upper position to a source of air supply under pressure, whereby the surplus liquor is extracted from the yarn and the yarn dried on the beam in the machine. 95
3. A dyeing machine comprising an open top tank, a lower clamping mechanism on one end of the tank, an upper clamping mechanism on the same end of the tank, a rotary pump, pipe connections from the pump to the opposite end of the tank, and pipe connections from the pump to the bottom of the tank. 105
4. A dyeing machine comprising an open top tank, a lower clamping mechanism on one end of the tank, an upper clamping mechanism on the same end of the tank, a rotary pump, pipe connections from the pump to the opposite end of the tank, pipe connections from the pump to the bottom of the tank and a pipe connection from the tank on a line with and in axial alignment with the upper clamping mechanism. 110
5. A dyeing machine comprising twin tanks each tank having a dyeing chamber closed at the bottom sides and ends and open at the top, the ends of the tank extending above the open top of the dyeing chamber, a base having legs supporting each tank, a lower screw-clamp on the end and having a hand wheel on its outer end and a head on its inner end in the dyeing chamber, an upper screw-clamp on the raised end having a hand wheel on its outer end and a head on its inner end over the 125 130

dyeing chamber, a rotary pump, pipe connections from the pump to the end of each tank, pipe connections from the pump to the bottom of each tank and a pipe connection from the raised end of each tank on a line with and in axial alinement with its corresponding upper screw clamp.

In testimony whereof, I have signed my name to this specification in the presence of two subscribing witnesses.

SAMUEL BARKER.
